Myron G. Clear

A detailed technical drawing of a lock cylinder's internal mechanism. It features a central circular hub with a small circular hole. Surrounding this are several concentric rings and a central pin. The numbers 25, 10, 25, 25, 25, and 87 are printed around the cylinder's body, likely indicating specific dimensions or part numbers. The drawing is rendered in black and white with fine lines and cross-hatching.

UNITED STATES PATENT OFFICE.

JAMES H. COURNYER, OF OSKALOOSA, IOWA.

SIPHON CREAM-REMOVER.

1,237,871.

Specification of Letters Patent. Patented Aug. 21, 1917.

Application filed January 19, 1917. Serial No. 143,257.

To all whom it may concern:

Be it known that I, JAMES H. COURNYER, a citizen of the United States, and a resident of Oskaloosa, in the county of Mahaska and State of Iowa, have invented a certain new and useful Improvement in Siphon Cream-Removers, of which the following is a specification.

My present invention relates generally to cream removers, and more particularly to devices in the nature of siphons for this purpose, my object being to improve existing types in the several instances to be hereinafter particularly pointed out, and to provide in addition thereto simple and effective means whereby the cream remover, as a whole, may be held firmly within the receptacle, such as, for instance, the ordinary milk bottle.

20 In the accompanying drawing illustrating my invention and forming a part of this application:

Figure 1 is a perspective view illustrating my present invention in operative position;

Fig. 2 is a vertical sectional view through the container and siphon in their operative relation;

Fig. 3 is a view partly in side elevation and partly broken away and in section of the upper portion of the siphon;

Fig. 4 is a horizontal section taken substantially on line 4—4 of Fig. 2, and

Fig. 5 is a detail elevation of the cap removed.

Referring now to these figures, my improved construction embodies a siphon, consisting of a relatively short upright leg or tube 10, and a relatively long inclined discharge tube 11, an upper horizontal connecting tube 12 connecting the tubes 10 and 11 adjacent their upper ends, it being noted that all three of the tubes are straight throughout, so as to render the cleaning of the siphon ready and effective and thus bring about a more sanitary condition at all times.

In use the upper end of the upright tube 10 is closed by a stopper 13, and the outer end of the connecting tube 12 is likewise closed by a stopper 14, each of these stoppers being readily removable for cleaning purposes.

It will further be noted that the upright intake tube 10, which is introduced within the bottle, jar, or other receptacle 15 in the

removal of the cream therefrom, is of substantially increased diameter with respect to the diameter of the outlet tube 11 and the connecting tube 12, so that with the assistance of certain features to be hereinafter described, the start of the siphoning action may be much more readily accomplished than is possible with the apparatus now in use, and but a single plunger within the tube 10 is required. The plunger is shown at 16 with its stem 17 projecting vertically through the stopper 13, with the disk 18 at its upper outer end forming a handle by which the plunger 16 may be raised and lowered, the stopper 13 being retained at all times except when it is desired to remove the stem for cleaning, by virtue of its particular construction which will now be described.

75 The stopper 14 may be in the nature of the usual cork, but stopper 13 is preferably in the nature of a cap as seen particularly in Fig. 5, to fit over the upper end of tube 10, with an internal washer 19, through which, and the upper end of the cap, the stem extends. The cap 13 has a lower bayonet slot 20 to receive the connecting tube 12 and by means of which the cap is normally retained in the position shown in Fig. 2, and adapted to be readily removed when it is so desired.

80 The lower end of the intake tube 10 is vertically slotted at 22, the slots extending above the plunger 16 in the lowermost position of the latter, as seen in Fig. 1, and the lower extremity of the tube 10 is further provided with inwardly projecting lugs 23 forming a limit of lowering movement of the plunger.

95 Thus, when the tube 10 is introduced within the cream, and plunger 16 lowered to rest upon the lugs 23, the cream finds its way into the upper portion of the slots 22 and outwardly into the tube 10 to the external 100 level or height of the cream, so that when the plunger 16 is raised not only is a column of cream drawn upwardly following the plunger, but the cream already within the tube 10 is lifted in a column and forced into 105 the tubes 11 and 12 so as to effectively produce siphon action without the necessity of a plunger in the discharge tube 11, as commonly used.

110 It is to be noted, furthermore, that the discharge tube 11 and connecting tube 12, are of the same cross sectional area, and that the

disk or plunger 18 forming a handle for the stem 17 is of a diameter adapted to interfit said tubes 11 and 12, so that the latter may be thoroughly cleaned by introducing the disk 18 therein after its removal with the stopper 13 from the tube 10.

Normally the upper end of the tube 10 and the outer end of the tube 12, are closed by the stoppers 13 and 14, as above described, the former of which deflects the column of cream above the plunger 16 into the tube 12 and the latter of which forces the cream to seek its outlet through the discharge tube 11.

15 The siphon as a whole, described as above, is held within a receptacle, such for instance as a bottle 15, by means of a curved spring clasping member 24 extending partly around and detachably engaging the tube 10, with 20 its extensions 25 bent back thereon and outwardly to form curved spring clasping arms 26 engageable outwardly against the inner surface of the bottle mouth, as shown particularly in Figs. 1, 2, and 4, the ends of the 25 spring arms 26 having inwardly opposing portions provided with upstanding finger pieces 27 whereby the latter may be drawn together in inserting the same within and removing the same from operative position, 30 the compression upon the arms 26 within the bottle mouth serving to increase tension of the clasping member 24 around the tube 10.

It is obvious from the foregoing that my 35 invention provides simple and improved means for the purposes set forth, adapted to effectively and efficiently perform the functions and carry out the objects first above stated, and one which will obviate the necessity of other tools and implements for cleaning purposes, as well as necessitating the use of but a single plunger for producing the 40 desired siphon action.

Copies of this patent may be obtained for five cents each, by addressing the "Commissioner of Patents, Washington, D. C."

I claim:—

1. A siphon of the character described comprising inlet and outlet tubes, of which the intake tube is of greater cross sectional area than that of the outlet tube, a plunger slidably interfitting the intake tube, a stem connected to the said plunger, and a disk upon the upper exterior end of the stem 45 adapted to slidably interfit the outlet tube.

2. A siphon of the character described, comprising an intake tube open at its lower end, a connecting tube extending laterally from said intake tube adjacent the upper 55 end of the latter, an outlet tube depending from the said connecting tube, said connecting and outlet tubes being of similar cross sectional area, reduced as compared to the area of the intake tube, a plunger slidably 60 interfitting the intake tube, and a stem connected at one end to the plunger and having a disk at its opposite end forming a handle and adapted to slidably interfit the said connecting and outlet tubes.

65 3. A siphon of the character described, including intake and outlet tubes, a connecting tube extending from the intake tube adjacent the upper end of the latter and communicating with the upper end of the outlet tube, said intake tube being open at both ends, a plunger therein, and a stopper normally closing the upper end of the intake tube and consisting of a cap fitting over the same, having an internal washer and a lower bayonet slot receiving the adjacent portion of the connecting tube whereby to normally support the cap in position.

JAMES H. COURNYER.
